United States Patent Office.

JOHN A. HAFNER, OF COMMERCE, MISSOURI.

Letters Patent No. 96,225, dated October 26, 1869.

IMPROVEMENT IN HORSE-POWER CONNECTION.

The Schedule referred to in these Letters Patent and making part of the same.

To all whom it may concern:

Be it known that I, JOHN A. HAFNER, of Commerce, in the county of Scott, and State of Missouri, have invented certain new and useful Improvements in Horse-Power Connections; and do hereby declare that the following is a full, clear, and exact description thereof, reference being had to the accompanying drawings, and to the letters of reference marked thereon, making a part of this specification.

The nature of my invention consists in the construction and arrangement of a "horse-power connection," as will be hereinafter fully set forth.

In order to enable others skilled in the art to which my invention appertains, to make and use the same, I will now proceed to describe its construction and operation, referring to the annexed drawings, in which—

Figure 1 is a vertical section of the connection, having the spring removed;

Figure 2 is an inside view of the casing, showing the spring in position; and

Figure 3 is an inside view of the cover or lid to the casing.

A represents the casing, which is provided, in its centre, with a dome-shaped projection, B, within which the tumbling-rod D is placed, said rod being secured by a thumb-screw, E, which passes through a continuation or extension of the dome B, outside of the casing.

On the dome B is placed the clutch C, the inner end of which is shaped in the form of a hub, so as to fit and turn on the dome.

The hub-portion of the clutch C is, at each end, provided with a circular flange, a, between which the inner coil of the spring F lies.

The spring F consists of two or more leaves, riveted together at one end and bent as a hook to fit in slots on the flanges a a, or in the hub itself.

The outer leaf, e, of the spring F, which I prefer making the longest, is, at its outer end, bent in the form of a ring, so as to fit within one of the semicircular projections b, on the casing, and that the bolt which passes through said projection to secure the cover to the casing, may pass through said ring, and thus secure that end of the spring to the casing, while the other, or inner end, is, as above-mentioned, secured firmly in the hub-part of the clutch C.

The outer leaf e, is, on its inner side, at suitable intervals, provided with smaller leaves, i i, riveted, at their inner ends, to the outer leaf, thus strengthening the same.

The cover G fits around the clutch C, and has suitable projections to correspond with the projections b on the casing A, and is secured to the casing by means of bolts, d d, passing through the said projections, which bolts are then fastened by burrs or nuts, c c, one of said bolts passing, as above-mentioned, through the ring or loop formed on the outer end of the spring F.

On the inside of the cover G is a circular recess, f, which is provided with two stops, g g, and on the outer side of the outer flange a is another stop or lug, h, which works in the recess f, between the stops g g.

These lugs or stops are so arranged that the spring cannot be turned backward, and, when turned forward, it is only for a certain distance, thus, in a great measure, preventing the spring from becoming broken.

In other horse-power connections, the clutch and casing have, as a general thing, been formed in one piece, so that when the clutch has become worn out, the casing also had to be thrown away; but, by forming them in the manner above described, I save the casing, and can readily remove the clutch and replace it with a new one when necessary.

The present invention is an improvement upon the patent granted me February 2, 1869.

Having thus fully described my invention,

What I claim as new, and desire to secure by Letters Patent, is—

1. The casing A, constructed as described, with a dome-shaped projection, B, in the centre, substantially as and for the purposes herein set forth.
2. The clutch C, constructed as described, so as to fit over and turn freely on the dome B, substantially as and for the purposes herein set forth.
3. The cover G, having a recess, f, and stops g g, in combination with the lug or stop h, on the clutch C, substantially as and for the purposes herein set forth.
4. The combination of the casing A, dome B, clutch C, spring F, and cover G, all constructed as described, and operating substantially in the manner and for the purposes herein set forth.

In testimony that I claim the foregoing, I have hereunto set my hand, this 15th day of July, 1869.

JOHN A. HAFNER.
